[57] CLAIM

The ornamental design for an extractor tool for plastic risers, substantially as shown and described.

DESCRIPTION

FIG. 1 is a top perspective view of the extractor tool for plastic risers showing my new design;

FIG. 2 is a side elevational view thereof;

FIG. 3 is an end elevational view thereof;

FIG. 4 is an opposite end elevational view thereof;

FIG. 5 is a top plan view thereof.

The bottom view and opposing side view would appear as mirror images of FIGS. 5 and 2 respectively.
